UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

PERISCOPE.

Application filed July 15, 1922. Serial No. 575,244.

To all whom it may concern:

Be it known that I, HERMAN A. POPPENHUSEN, a citizen of the United States, residing at Hammond, in the county of Lake 5 and State of Indiana, have invented new and useful Improvements in Periscopes, of which the following is a specification.

This invention relates to periscopes for use with indicating instruments located at 10 points remote from the station of the observer and arranged so that images of said instruments may be visible at said station.

The invention has particular reference to the use of periscopes with steam boiler 15 gages set high above the floor of the boiler room, so that they may be easily and conveniently read by workmen standing on the boiler room floor, and thus avoid being required to use a step ladder or other device 20 to reach the gages for reading them as heretofore.

One object of my invention is to provide means whereby the variations registered by the gage while in use may be recorded 25 at the image at the end of the periscope at the observer's station, and thus be fully advised as to the conditions registered by the gage.

The invention consists further in the matters hereinafter described and more particularly set forth in the appended claims.

In the accompanying drawings,—

Fig. 1 is a side view showing a periscope of my invention, in position of use with a 30 steam boiler gage;

Fig. 2 is an enlarged vertical sectional view of said periscope; and

Figs. 3, 4, and 5 are sectional views taken 35 on lines 3—3, 4—4, and 5—5, respectively, of Fig. 2.

In the drawings; 1 indicates the front wall of a furnace, 2 the floor of the boiler room, 3 the upper water drum just inside the front wall and at a considerable distance above 45 the boiler room floor, and 4 an instrument for indicating the level of the water in the boiler. This instrument is connected with the drum 3 and has a glass gage tube 5, as customary in indicators of this general 50 kind.

Arranged in front of the front wall 1 is a periscope comprising a vertically disposed conduit 6 having at its upper end a box 7 positioned opposite the glass gage 5 and opening 55 toward the same. In the box is a mirror or

other reflector 8, arranged at the angle shown in Fig. 2 to receive an image of the glass 5.

The lower end of the conduit 6 extends toward the boiler room 2, and is there provided with a box 9 having an eye piece 10. 60 In the box 9 is a mirror, or reflector 11 arranged at the angle shown in the drawings and in a position to be viewed when the observer looks into the eye piece 10. The reflector 11 is aligned vertically with 65 the one 8 at the upper end of the conduit 6 and the arrangement of this is such that the image reflected by the upper reflector 8 into the lower one 11 of the glass water gage 5 is an upright one, as indicated by the dot 70 and dash line *a*, *b*, in Fig. 2. The eye piece 10 is on the eye level of a workman standing on the boiler room floor 2, and thus is in a position enabling a convenient and ready reading to be had at all times of the glass 75 gage 5 without being required to climb up to the gage to read it or to go with an inaccurate and faulty reading by attempting a reading at a distance as heretofore.

The periscope 6 may be secured in place in 80 any suitable manner, but in Fig. 1, I have shown brackets 12, 13 provided for this purpose. The bracket 12 is connected with the upper box 7 and clamped to the gage pipe, while the lower bracket 13 extends to 85 the front wall of the furnace setting and is bolted or otherwise secured thereto.

The conduit 6 may be constructed in any preferred way. In the drawing, however, I have shown the conduit made of a plurality of 90 rectangular pipe sections 14, 14. These have outside flanges 15 at their meeting ends to be engaged by the tie-bolts 16, as shown in the drawings. These tie-bolts also bolt the end boxes 7 and 9 to the adjacent sections 14. 95

During the operation of a boiler, the water therein surges back and forth between maximum and minimum levels with the result that there is a corresponding surge in the glass gage 5. It is difficult for the boiler tender to keep in mind the extent of this surge, and, in order to mark the limits of the surge, I provide in connection with the lower reflector 11 two pointers or indicators 17, 18, as shown in Fig. 3. These are 100 mounted in such a way that they may be adjusted lengthwise of the image appearing on the reflector 11 to mark the maximum and minimum movements of the surge in the gage tube 5. These indicators, as shown 105 110

in the drawings, are in the form of clips having spring-pressed finger pieces 19, 19, outside of the conduit 6 so that they may be readily grasped for adjusting them. The 5 box 9 at the side of the fingers 17, 18, is provided with an elongated slot 20, as shown in Figs. 2, 3, and 4, through which the indicating portion of the pointer extends, as illustrated in said figures.

10 To determine the approximate level of the water in the boiler, it is necessary to divide the length of the surge in half and to set an indicator at that point. To accomplish this I provide another indicator 21 in the 15 same form as the ones heretofore described, only on the side of the box 9 opposite the ones 17 and 18, as shown in Fig. 3. This indicator 21 extends into the box over the reflector 11 through an elongated slot 22 20 provided in the box 9, as shown in the drawings, and may be adjusted to indicate the approximately level of the water in the boiler by being positioned at a point midway between the maximum and minimum extent 25 of the surge which is reflected in the mirror 11.

The superintendent of the boiler room often instructs the boiler tender to maintain the level of the water between two predetermined points. To mark this, I provide indicators 23 and 24 made like the one previously described and extending through the slot 22, as shown in Fig. 3.

When the boiler tender observes that the 25 surge drops below the indicator 18, he knows that the level of the water in the boiler has dropped and it is time to start the feed pump. To enable him to know whether or not the pump is supplying enough water to 30 bring the water level to the point desired, it is necessary to know at what point the surge dropped prior to starting the pump. To do this I provide another indicator 25 made like the one previously described and extending into the box 10 over the reflector 11 35 through the slot 20. This may be adjusted to the lowest point of the surge after passing below the indicator 18 and the pump started to replenish the water supply. The 40 boiler tender can readily tell to what extent the pump is working by observing whether or not the level in the image is going above the pointer 25.

Be the device described, easy and convenient reading at all times of a boiler gage or other instrument is made possible, even though the instrument is set at such height above the station of the observer that it cannot be readily read from that station. The 45 image of the gage as reflected in the lower mirror 11 is upright so that the reading of the gage is rendered intelligible and seen as should the gage be viewed by having the observer climb to the height of the gage. The 50 provision of these indicators associated with

the lower reflector makes possible the accurate observance of conditions going on with respect to the changing of the water level in the boiler and thus enables the attendant to keep the furnace working efficiently.

70 While I have shown and described herein in detail a device of my invention, it is of course to be understood that the details of construction and arrangement of parts may be variously changed and modified without departing from the spirit and scope of my invention.

75 I claim as my invention:—

1. The combination with an instrument 80 adapted to indicate varying conditions and located at a point remote from the station of the observer, of a periscope extending between said instrument and the observer's station, said periscope being arranged to cause an image of said instrument to be visible at said station, adjustable indicators carried by said periscope at said image for recording the variations registered by said instrument, and means for supporting said periscope in place.

85 2. The combination with an instrument for indicating the level of a liquid in a container and located at a point remote from the station of the observer, of a periscope extending between said instrument and the observer's station, said periscope being arranged to cause an image of said instrument to be visible at said station, adjustable means carried by said periscope at the image 90 whereby the maximum and minimum levels and any intermediate level of the liquid in the container as registered by said instrument may be recorded at said image, and means for supporting said periscope in place.

95 3. The combination with an instrument 100 for indicating the level of water in a steam boiler and located at a point remote from the station of the observer, of a periscope extending between said instrument and the observer's station, said periscope being arranged to cause an image of said instrument to be visible at said station, adjustable means carried by said periscope at the image 105 whereby the extent of surge and the approximate water level registered by said instrument 110 may be recorded at said image, and means for supporting said periscope in place.

115 4. The combination with an instrument 120 for indicating the level of water in a steam boiler and located at a point remote from the station of the observer, of a periscope extending between said instrument and the observer's station, said periscope being arranged to cause an image of said instrument to be visible at said station, adjustable means carried by said periscope at the image 125 whereby there may be recorded at said image, the extent of surge, the approximate water level to be maintained, and the level when the feed pump is started.

5. A periscope of the character described, comprising a conduit with outwardly opening boxes at its ends, said boxes facing in opposite directions and having reflectors therein to cause an image of an object at one end of the conduit to be visible from the other end thereof, one of said boxes having slots therein on opposite sides of the reflector therein, and a set of adjustable indicators to be inserted into said box over said reflector through said slots.
6. A periscope of the character described, comprising a conduit with outwardly opening boxes at its ends, said boxes facing in opposite directions and having reflectors therein to cause an image of an object at one end of the conduit to be visible from the other end thereof, one of said boxes having a slot adjacent the reflector therein, and adjustable indicators to be inserted into said box over said reflector through said slot.
10. A periscope of the character described, comprising a conduit with outwardly opening boxes at its ends, said boxes facing in

opposite directions and having reflectors therein to cause an image of an object at one end of the conduit to be visible from the other end thereof, one of said boxes having slots therein on opposite sides of the reflector therein, and a set of adjustable indicators to be inserted into said box over said reflector through said slots.

In testimony that I claim the foregoing as my invention, I affix my signature this 12th day of July, A. D. 1922.

HERMAN A. POPPENHUSEN.
